(57) **CLAIM**

The ornamental design for a non-invasive analyte sensor as shown and described.

DESCRIPTION

FIG. 1 is a top perspective view of a non-invasive analyte sensor according to our new design.

FIG. 2 is a front side view thereof; the rear side view is identical.

FIG. 3 is a left side view thereof; the right side view is identical.

FIG. 4 is a top view thereof; and,

FIG. 5 is a bottom view thereof.

The dot-dash broken lines indicates a boundary between claimed and unclaimed subject matter. The dash-dot broken lines indicate unclaimed subject matter and form no part of the claimed design.
